MONROE GUETT, OF HARTFORD, CONNECTICUT, ASSIGNOR TO THE HART & HEGEMAN MANUFACTURING COMPANY, OF HARTFORD, CONNECTICUT, A CORPORATION OF CONNECTICUT.

ELECTRIC SWITCH.

1,347,629.

Specification of Letters Patent. Patented July 27, 1920.

Application filed July 15, 1919. Serial No. 310,932.

To all whom it may concern:

Be it known that I, MONROE GUETT, a citizen of the United States, residing at Hartford, in the county of Hartford and State 5 of Connecticut, have invented certain new and useful Improvements in Electric Switches, of which the following is a specification.

This invention relates to electric switches. 10 I have several motives in view, among the principal of them being a very efficient way of insulating, in an inexpensive manner, the circuit-controlling or switching member of the switch. While the invention in the art 15 in which it lies is capable of general use, it is of particular advantage when incorporated in an oscillating snap switch. In the drawings accompanying and forming part of the present specification, I have shown 20 in detail, a form of embodiment of the invention, which to enable those skilled in the art to practice the same will be set forth fully in the following description. I am not restricted to this disclosure; I may de- 25 part therefrom in several respects within the scope of the invention defined by the claims following said description.

Referring to said drawings:

Figure 1 is a side elevation of a switch 30 embodying the invention.

Fig. 2 is a bottom plan view of the switch. Fig. 3 is a longitudinal section on the line 3—3 of Fig. 2 looking in the direction of the arrows.

Fig. 4 is a cross section on the line 4—4 of Fig. 1 looking in the direction of the arrows.

Like characters refer to like parts throughout the several views.

The supporting body of the switch may be 40 of any suitable character. That shown comprises a block as 2, of insulating material. To the opposite faces of this block are suitably fastened contacts as 3, duplicates in effect of each other and of some conducting 45 material. The contacts or terminals 3 are furnished with suitable means, as the screws 4, by which wires or their equivalents may be connected to the respective contacts. At 50 opposite sides of the insulating body are shown as mounted, the duplicate plates or check pieces 5, which may be of metal and

which are connected to each other and to the body 2 in some convenient way, screws 6 being shown for the purpose. The plates 5 project forwardly from the body 2, their upper ends being integrally united by the plate 7. The several plates 5 and 7 constitute a convenient way of sustaining the switching or circuit-controlling member and the actuating means therefor.

As will be understood, the switching or circuit-controlling member may vary as to character, that shown being denoted in the general way by 8. Likewise, the actuator for the switching or circuit-controlling member may also vary, that shown is designated by 9 and is in the form of a lever pivoted between the plates 5, as at 10, and extending through a slot as 11 in the top plate 7.

The switching member 8 as shown involves in its make-up duplicate side arms or pieces as 12 of some insulating material, such as vulcanized rubber. The arms or pieces 12 are in transverse register and they 75 lie across the outer surfaces of the plates 5. They are comparatively flat and are somewhat elongated. At their upper ends they have elongated slots 13, in registration with each other, through which and also through the side plates 5, rivets or pins as 14, which may be of metal and constituting suitable pivot means, are adapted respectively to extend. The switching or circuit-controlling member 8 is shown as being in the off position in Fig. 1, at which time the mounting rivets 14 are against the upper ends of the transversely aligned slots 13. The arms 12 are shown as having at their lower ends, elongated registering slots as 15, adapted 80 to receive the metallic pin 16, which mechanically bridges the arms 10. The ends of the pin 16 are headed. This pin 16 constitutes a convenient bridging member for electrically bridging across the complementary contacts 3, at their free resilient ends, when the switching member is in circuit closing position.

The arms or side pieces 12 of the switching member 8 of course properly insulate 100 electrically the supporting rivets or pivots 14 from the bridging member or pin 16 in

the several positions of the switching member or circuit-controlling member. It will, of course, be obvious from what I have already noted, that I am not restricted to the showing made hereby as the invention from certain angles at any rate involves broad relations. As an illustration, I have an oscillating snap-switch. In the present case, however, the actuator 9, which is manually operable constitutes the prime factor for effecting the action of the switching member.

It is desirable to give a brief description of the construction and action of the remaining parts of the switching or circuit-controlling member 8. Between the arms or check pieces 12 and transversely alined therewith are arms as 17 counterparts of each other, of some insulating material, and the outer and lower notched ends of which fit a peripheral groove or channel 18 in the bridging member 16. These arms 17 receive around them the coiled spring 19 which bears at its outer end against the disk 20 supported by the shoulders 17' of the arms 17, and at its upper end acts against a like disk 21, which engages against the pin 22, fitting companion open ended slots 23, in the arms 17. The arms 17, it will be apparent, insulate the actuating mechanism of the switch, from the bridging member 16. The pin 22 fits a notch in the lower or short branch of the rock lever 9.

The switching member 8 is shown as off in Fig. 3, for instance. To move it to on, the following action takes place. The ball or upper end of the rock lever 9 will be thrust to the left so that the short or inner arm of the rock lever will be moved to the right. As a result, the pin 22 is moved downwardly carrying the disk 21 therewith, and compressing the spring 19, and at the same time moving the switching member 8 toward the dead center line of the switch, at which point the spring will be released and will re-act and thus snap the switching member to circuit closing position and carry the rounded ends of the projecting member or pin 16 against the free ends of the contacts 3.

50 The dead center line of the switch shown, intersects the axis of motion of the switching member 8 and the axis or center of the bridging member or pin 16.

What I claim is:—

55 1. An electric switch comprising a swinging arm of insulating material, a contact bridging part of conducting material, supported at the free portion of the insulating arm, an actuator mounted for back and forth movement and provided with a pin, a spring, and an insulating arm supporting the spring, the spring being interposed between the pin and the bridging member, and the pin acting on each motion of the actuator, to condition 60 the spring to snap the switching member,

after said pin has crossed the dead center line which intersects the axis of motion of the switching member and the center of the contact-bridging part.

2. An electric switch comprising a body 70 of insulating material, contacts fastened to the body, plates fastened to opposite sides of the body, a swinging switching member pivotally supported by the body and comprising side arms of insulating material disposed outside of the respective plates and a contact-bridging member of conducting material extending between and outwardly beyond the side arms, an actuator for the switching member mounted for back and forth movement, spring means movable with the switching member, the actuator on each of its movements conditioning the spring means to impart a snap movement to the switching member when released by the actuator to thus cause the switching member to assume "on" and "off" positions, said bridging member when the switching member is in the "on" position engaging said contacts.

3. An electric switch comprising a swinging switching member having an arm of insulating material and a contact-bridging member of conducting material carried by said arm, an actuator for the switching member, mounted for back and forth movement, a pin fitted against the bridging member, a spring supported by and around the pin, the pin swinging with the switching member and being of insulating material, the actuator on each of its movements conditioning the spring to impart a snap movement to the switching member when freed by the actuator.

4. An electric switch comprising a swinging switching member having an arm of insulating material and a contact-bridging member of conducting material carried by said arm, an actuator for the switching member mounted for back and forth movement, a pair of pins of insulating material fitted against the bridging member, a spring supported by and around the pins, the pins swinging with the switching member, the actuator on each of its movements conditioning the spring to impart a snap movement to the switching member when freed by the actuator.

5. An electric switch comprising a swinging switching member having an arm of insulating material and a contact-bridging member of conducting material carried by said arm, an actuator for the switching member mounted for back and forth movement, a pair of arms of insulating material 125 fitted against the bridging member and each having a shoulder, a washer around the pins and fitted against said shoulders, a coiled spring around the pins and supported at one end by the washer, a second washer engag- 130

ing the opposite end of the spring, said pins having slots, a pin fitted in said slots and engaging said second washer, the actuator being adapted to engage said pin on each 5 of its movements and acting to condition the spring to impart a snap movement to the switching member when it is freed.

In testimony whereof I affix my signature in the presence of two witnesses.

MONROE GUETT.
